ELECTRIC IRON

Filed May 17, 1926

UNITED STATES PATENT OFFICE

FRANK H. HANLEY, OF DETROIT, MICHIGAN, ASSIGNOR TO HANLEY MANUFACTURING COMPANY, OF DETROIT, MICHIGAN, A CORPORATION OF MICHIGAN

ELECTRIC IRON

Application filed May 17, 1926. Serial No. 109,603.

This invention relates to an electric iron, and has special reference to that class of irons that may be manually or automatically controlled, to avoid overheating and waste of electrical current. The manual control is ordinarily by a switch on or in proximity to the handle of the iron, and the automatic control may be by a thermostatic device.

My invention aims to provide a manual and automatic control device that may be easily and quickly applied to various types of electrically heated irons, the device including manual and automatic control mechanisms which are compactly arranged on the iron with the manual control in proximity to the iron handle so that the hand gripping the iron handle may be used to switch on and off the electric current. The thermostatic control is within an effective heating zone of the iron and provision is made for regulating the action of this control.

My invention further aims to furnish a positive throw switch of the plunger actuated type with a novel trip member that is manually set for release by a thermostatic device, and the thermostatic device is provided with means so that it may be manually actuated at any time to cause the switch to be actuated to cut off the electric current and the plunger

of the switch restored to normal position.

The details of construction entering into my electric iron will be hereinafter specifically described and then claimed, and reference will now be had to the drawing wherein

Figure 1 is a plan of the iron partly broken away and partly in section;

Fig. 2 is a side elevation of the iron with the manual and automatic control device in longitudinal section showing an "off" position of the device;

Fig. 3 is a horizontal sectional view of a portion of the iron;

Fig. 4 is a cross sectional view taken on the line IV—IV of Fig. 1;

Fig. 5 is a detail view of the control device in an "on" position; and

Fig. 6 is a cross sectional view taken on the line VI—VI of Fig. 3.

50 In the drawing, the reference numeral 1

denotes a conventional form of electric iron having handle supports 2 and 3 connected by tie rods 4 supporting a handle 5. The handle support 2 has a socket 6 for a plug 7 carried by a leading-in conductor 8. The iron 1 ordinarily has a cover held in place by a screw bolt 9 and I utilize this screw bolt and the handle support 3 as a means of retaining my attachment in engagement with the iron.

The attachment comprises a plate or platform 10 with its forward end provided with a side wall 11, a front wall 12, and a tang 13, said tang being placed in engagement with the support 3 and the tie rod 4 for holding the forward end of the platform 10 substantially on the cover of the iron.

The rear end of the platform 10 has a longitudinal slot 14 adjacent its inner edge and this edge of the platform rests on and is adjustably connected to a cleat 15 having a slot 16 for a nut equipped clamping screw 17 which extends through the slot 14 so that the cleat and platform may be clamped together. The cleat is slotted at 18 to fit under the screw bolt 9 and it is by virtue of said cleat and its adjustment relative to the screw bolt 9 and the platform 10 that the attachment is applicable to various sizes or types of electrically heated irons.

Mounted on the platform 10 and cooperating with the walls 11, and 12 in forming a housing is a casing 19, preferably made of insulation material. In this casing is placed a positive throw switch 20 including stop members 21 for a pivoted switch plate 22 engageable with resilient switch plates 23 held by binding posts 24 to which are connected leading-out wires 25. These wires extend through a tubular guard 26 and into the plug 7, where suitable connections are made with the conductor 8. The guard 26 may be held in place on the platform 10 by a clip 27 held by the nut equipped screw 17.

The pivoted switch plate 22 includes a plunger member 28 supported on a bracket 29 on which is mounted the switch 20. Operable through the bracket 29 and loosely connected to the plunger member 28, as at 30, is a vertically disposed plunger 31 having the upper end thereof provided with

5 a finger piece 32, protruding from the casting 19 and made of insulation material. This finger piece is in proximity to the forward end of the handle 5 and is normally supported in a raised position by the expansive force of a coiled spring 33 encircling the plunger 31, between the finger piece 32 and an extension 34 of the switch 20. The finger piece 32 may be readily depressed by 10 the thumb of a hand gripping the handle 5 and such depression is adapted to actuate the pivoted plunger member 28 and throw the switch plate 22 from the "off" position shown in Fig. 2 to the "on" position shown 15 in Fig. 5.

Pivottally mounted on the platform 10 below the switch 20, as at 35 is a trip member 36. This trip member has an overhanging hook shaped portion 37 adapted to overlie a 20 portion of the plunger member 28, as shown in Fig. 5 and hold the plunger member with the plunger 31 lowered and the switch in an "on" position. To place the trip member 36 in engagement with the plunger member 28, said trip member has a depending finger piece 38 extending through a slot 39 in the side wall 11, and when the finger piece 32 is depressed and so held, the finger piece 38 can be shifted to place the overhanging portion 25 37 of the trip member 36 in engagement with the plunger member 28.

To hold the trip member 36 in its adjusted position, said trip member has a lateral keeper 40 engageable by a latch 41 extending upwardly through a slot 42 in the platform 10. The latch 41 is on the extreme forward end of a resilient or flexible laminated thermostatic strip 43 that is susceptible to flexure by heat radiated by the iron. The 35 rear end of the thermostatic strip 43 is attached to the rear end of the platform 10, as at 44, and the strip 43 and the platform 10 are provided with registering slots 45 for a nut equipped screw bolt 46. The nut 47 40 of the screw bolt 46 bears on the platform 10 and is slidable thereon and adapted to be fixed relative to the platform. This nut equipped screw bolt constitutes a device for regulating the flexure of the thermostatic strip, whereby said strip may be made more or less active for the purposes of an automatic control or strip release device.

Attached to the thermostatic strip 43, between the screw bolt 46 and the latch 41 is 55 a post 48 extending through the platform 10 and provided with a button head 49. Encircling the post 48, between the head 49 and the platform 10 is a coiled expansion spring 50. The tension of the spring does not interfere with flexure of the thermostatic strip 43, but supports the button head 49 so that this head may be depressed to lower the forward end of the thermostatic strip 43 and release the trip member 36. The elements 60 65 48 to 50 inclusive constitute means for manu-

ally actuating the thermostatic strip or device should it be desired to open the switch and cut off the supply of electrical current to the iron, before such is automatically accomplished by flexure of the thermostatic strip. 70

In order that the trip member 36 may be swung on its pivot or actuated to release the plunger member 28, when the keeper 40 is released by the latch 41, a coiled retractile 75 spring 51 is attached to the overhanging portion 37 of the trip member 36 and an upstruck lug 52 of the platform 10. See Fig. 3.

Assuming the iron is in an "off" position, as shown in Fig. 2, and it is desired to turn 80 on the current to heat the iron 1 preparatory to using the same. The finger piece 32 is depressed placing the spring 33 under compression. The plunger member 28 is rocked to throw the switch plate 22 into engagement 85 with the yieldable contact members or plates 23. A circuit is then completed for heating the iron. While the finger piece 32 is momentarily held depressed, the finger piece 38 is shifted to secure the plunger member 28 90 in its shifted position, and when the trip member 36 is so actuated the resilient thermostatic strip 43 places its latch 41 in the path of the extension 40 to hold the trip member. 95

As the iron becomes heated it may be used and if it becomes too hot the strip 43 releases the trip member 36, which in turn opens the switch 20 and permits the spring 33 to restore the plunger and its finger piece to normal raised position. 100

It will be noted that the electrical connections are insulated and may be safely used; that other switches than that shown may be employed in connection with the trip member, and that the attachment is applicable to irons other than of the plug type shown. For these reasons I do not care to confine my invention to the precise construction and arrangement of parts other than defined by the 110 appended claims.

What I claim is:—

1. In combination with a switch for controlling an electric current, a spring supported plunger adapted to be depressed and held to close said switch, said plunger being adapted to be released to open said switch, and a plunger member connected to said plunger and switch for actuating the latter, manually and automatically operated means 115 for controlling said plunger member, said means including a trip member engageable with said plunger member to hold it with said switch closed, and a thermostatic device controlling movement of said trip member to 120 release said plunger member.

2. The combination called for in claim 1, further characterized by means carried by the thermostatic device to facilitate manual actuation thereof. 125

3. The combination called for in claim 1, further characterized by means adapted to regulate the action of said thermostatic device.
4. The combination called for in claim 1, further characterized by an adjustable platform supporting said switch and thermostatic device.

10 In testimony whereof I affix my signature.
FRANK H. HANLEY.
